INVENTOR.

No. 36,807.

Patented February 16, 1904.

UNITED STATES PATENT OFFICE.

WALTHER HELBIG, OF NEW YORK, N. Y., ASSIGNOR TO THE KURSHEEDT MANUFACTURING COMPANY, OF NEW YORK, N. Y., A CORPORATION OF NEW YORK.

DESIGN FOR A COLLAR.

SPECIFICATION forming part of Design No. 36,807, dated February 16, 1904.

Application filed January 23, 1904. Serial No. 190,408. Term of patent 2½ years.

To all whom it may concern:

Be it known that I, WALTHER HELBIG, a citizen of the Empire of Germany, residing in the borough of Manhattan, city, county, and State of New York, have invented a certain new, original, and ornamental Design for Collars, of which the following is a specification, reference being had to the accompanying drawing, forming a part hereof.

- In this drawing the figure shows my design for collars, the repeats being shown in outline.

What I claim as new, and desire to secure by Letters Patent, is—

The ornamental design for a collar, substantially as herein shown.

WALTHER HELBIG.
